US00D590386S

(12) **United States Design Patent**
Leith et al.

(10) **Patent No.:** US D590,386 S
(45) **Date of Patent:** ** Apr. 14, 2009

(54) **MOVABLE SUPPORT ELEMENT FOR A
HANDSET**

(75) Inventors: **Daren Leith**, West Hills, CA (US);
Daniel Dhondt, Espoo (FI)

(73) Assignee: **Nokia Corporation**, Espoo (FI)

(**) Term: **14 Years**

(21) Appl. No.: **29/318,104**

(22) Filed: **May 13, 2008**

Related U.S. Application Data

(63) Continuation of application No. 29/250,715, filed on Nov. 28, 2006.

(30) **Foreign Application Priority Data**

Jun. 14, 2006 (FI) M20060130

(51) **LOC (9) Cl.** 14-03

(52) **U.S. Cl.** D14/248; D16/208

(57) **CLAIM**

The ornamental design for a movable support element for a handset, as shown and described.

DESCRIPTION

FIG. 1 is a perspective front view of a movable support element for a handset showing our new design;

FIG. 2 is a front view thereof; and,

FIG. 3 is a perspective front view of the movable support element for a handset in an alternative in-use position.

The rectangular broken line showing within the claimed area represents the bounds of the claimed design, while all other broken lines are directed to environment and are for illustrative purposes only; the broken lines forms no part of the claimed design.
